US00D944431S

(12) **United States Design Patent** (10) **Patent No.:** **US D944,431 S**
(45) **Date of Patent:** **** Feb. 22, 2022**

(54) **COMBINED LIGHT AND SPEAKER**

(71) Applicant: **SONY CORPORATION**, Tokyo (JP)

(72) Inventor: **Yujin Morisawa**, Tokyo (JP)

(73) Assignee: **SONY CORPORATION**, Tokyo (JP)

(**) Term: **15 Years**

(21) Appl. No.: **29/684,371**

(22) Filed: **Mar. 20, 2019**

(30) **Foreign Application Priority Data**

Dec. 27, 2018 (JP) D2018-028733

(51) **LOC (13) Cl.** **26-05**

(52) **U.S. Cl.**

USPC **D26/52**

(57) **CLAIM**

The ornamental design for a combined light and speaker, as shown and described.

DESCRIPTION

FIG. 1 is a perspective view of a combined light and speaker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

(Continued)

The broken lines illustrating portions of the combined light and speaker form no part of the claimed design.

1 Claim, 7 Drawing Sheets
